UNITED STATES PATENT OFFICE.

DANIEL W. TOWER, OF GRAND RAPIDS, MICHIGAN.

DESIGN FOR A HINGE MEMBER.

SPECIFICATION forming part of Design No. 35,238, dated October 29, 1901.

Application filed September 16, 1901. Serial No. 75,629. Term of patent 34 years.

To all whom it may concern:

Be it known that I, DANIEL W. TOWER, a citizen of the United States, residing at Grand Rapids, in the county of Kent and State of Michigan, have invented and produced a new and original Design for a Hinge Member, of which the following is a specification.

This invention relates to a new and original design for a hinge member, and the essential features reside in the design as illustrated in the accompanying drawings, wherein—

Figure 1 is a perspective view of a hinge member embodying the features of the design. Fig. 2 is a transverse vertical section on the line 2 2, Fig. 1. Fig. 3 is an edge elevation of the same.

The design is characterized by a leaf 1, having intermediate transverse projections 2 with convex edges and apertures therethrough. 20 These projections run into concave recesses

3 to form a leaf-like extremity 4, also having an aperture therein. Near the inner terminal of the leaf 1 an offset 5 is located and continues into a transversely-reduced member 6 with parallel side edges 7 and having a curved 25 terminal 8. A hollow tapered rib 9 extends from the curved terminal 8 longitudinally through the center of a greater portion of the leaf.

Having thus described the invention, what 30 is claimed as new is—

The design for a hinge member, as herein shown and described.

In testimony that I claim the foregoing as my own I have hereto affixed my signature in 35 the presence of two witnesses.

DANIEL W. TOWER.
